UNITED STATES PATENT OFFICE.

EMIL PASSBURG, OF BERLIN, GERMANY.

CABLE-DRYING APPARATUS.

No. 839,191.

Specification of Letters Patent.

Patented Dec. 25, 1906.

Application filed February 10, 1906. Serial No. 300,384.

To all whom it may concern:

Be it known that I, EMIL PASSBURG, engineer, of 33 Brückenallee, Berlin, in the Empire of Germany, have invented certain new and useful Improvements in Cable-Drying Apparatus, of which the following is a full specification.

The subject-matter of the invention is an apparatus or device for drying cables under a vacuum, in which the cable while shut off from the air is continuously drawn through a vacuum-pipe, which serves as a drying apparatus. The cable also leaves the pipe without passing through stuffing-boxes, glands, or the like, which in consequence of their being tightly closed round the sheath of the cable might easily damage the same, particularly if the cable be provided with a paper sheath. The end of the vacuum drying-pipe through which the cable enters has an air-tight connection with a chamber which after the cable wound upon a rotary drum has been introduced thereinto is exhausted simultaneously with the drying-pipe. The exit end of the vacuum drying-pipe dips into an impregnating liquid contained in an open vessel, which liquid when the vacuum drying-pipe has been exhausted is sucked up into the tube to a height corresponding, approximately, to the height of the barometer, so that air is prevented from entering the drying-pipe, said liquid thereby serving as a stuffing-box through which the cable passes.

In the accompanying drawings, Figure 1 is a section through the whole drying apparatus, while Fig. 2 is a cross-section through the vacuum drying-pipe on the line A A of Fig. 1.

A chamber *a* is provided, which is preferably cylindrical in shape, into which vessel the cable *c*, wound upon a drum *b*, is placed, the drum with the cable thereupon being inserted from above through an opening adapted to be hermetically closed by a cover or door. The drum *b* is adapted to rotate directly in the vessel *a* or in bearings supported by a frame arranged on a trolley or like carriage.

The vessel *a* itself may be fitted with heating devices *d* for the purpose of heating and partially drying the cable. The vacuum drying apparatus is connected in an air-tight manner with the vessel *a*, said vacuum drying apparatus consisting of one or more pipes *e* of comparatively small diameter which

have air-tight connection and cross connection with each other, said pipes being surrounded by a jacket *f*, which is heated by any suitable means. The heat from this jacket is radiated upon the cable, which, as it moves forward, is preferably supported on rollers *g*, as indicated by the arrows in Fig. 2, the entire surface of the cable as it passes through the drying-pipe being thus subjected to a uniform degree of heat. As a result the water contained in the sheath of the cable is quickly converted into steam under the joint action of the heat and the vacuum which prevails in the heating-pipe *e*. This steam is afterward condensed to water in a condenser *k* of suitable construction. From the pipe *e* suitable pipes lead to the air-pump or to the condenser. The pipe *e* and its jacket *f* may be either straight, as shown in the drawings, or it may be arranged in a coil if circumstances render that construction expedient. The exit end *h* of the pipe where the cable leaves the same dips into the impregnating liquid *l*, which is contained in the open vessel *i*.

When a vacuum is created in the pipe *e*, the suction will cause the liquid *l* to rise therein to its barometric height, which of course will vary as different liquids are used from time to time, and accordingly the liquid which rises in the pipe prevents the admission of air thereinto, serving likewise as a stuffing-box through which the cable may pass. The cable is wound upon a drum *n*, which rotates within the vessel *i* and is thereby continuously drawn through pipe *e* and unwound from drum *b*. Suitable heaters *m*, placed in the vessel *i*, keep the liquid *l* raised to the temperature at which it most readily impregnates the pores of the cable-sheath.

Having thus described my said invention, what I claim, and desire to secure by Letters Patent, is—

1. In a device of the character described, the combination of a pipe, means for exhausting and means for heating the same, a cable-holding chamber having an air-tight connection with one end of said pipe, and a vessel into which the other end of said pipe dips.

2. In a device of the character described, the combination of a plurality of pipes, means for exhausting and means for heating the same, a cable-holding chamber having an air-tight connection with one end of

said pipes, and an open vessel adapted to hold an impregnating liquid into which the other ends of said pipes dip.

3. In a device of the character described, 5 the combination of a pipe, means for exhausting the same, one end of said pipe having an air-tight closure, an impregnating liquid rising in the other end of said pipe, and means for drawing a cable through said pipe 10 and said liquid.

4. In a device of the character described, 15 the combination of a pipe, a chamber in connection therewith, means for exhausting said pipe and said chamber, an impregnating liquid being drawn by suction into said pipe, and means for causing a cable to pass from said chamber and through said pipe and said liquid.

5. In a device of the character described, 20 the combination of a drying-pipe, means for exhausting the same, an impregnating liquid being drawn into said pipe when exhausted, and means for causing a cable to pass continuously through said drying-pipe and 25 through said liquid.

6. In a device of the character described, 25 the combination of a drying-pipe, means for exhausting the same, a condenser connected with said pipe, an impregnating liquid in one 30 end of said pipe preventing access of air thereto, and means for causing a cable to pass through said pipe and said liquid.

7. In a device of the character described, 35 the combination of a pipe, means for drying a cable in said pipe, means for removing the steam therefrom, and means for passing the dried cable through an impregnating liquid as said cable leaves said pipe.

8. In a device of the character described, 40 the combination of a pipe, an air-tight cham-

ber in connection with one end thereof, a cable passing from said chamber and through said pipe, means for exhausting said pipe and said chamber, and means for preventing access of air through the other end of said pipe, said means serving, also, to impregnate 45 said cable.

9. In a device of the character described, 50 the combination of a pipe, means for hermetically sealing one end thereof, means for exhausting the pipe, and means independent of said pipe for preventing access of air through the other end thereof, said means serving, also, to impregnate the cable passing through 55 said pipe.

10. In a device of the character described, 60 the combination of a pipe, drying means, exhausting means, and impregnating means, and means for causing a cable in said pipe to be successively dried and impregnated.

11. In a device of the character described, 65 the combination of a pipe, means for exhausting and means for heating the same, a cable-holding chamber having an air-tight connection with one end of said pipe, and an open vessel adapted to hold an impregnating liquid into which the other end of said pipe dips.

12. In a device of the character described, 70 the combination of a pipe, means for exhausting and means for heating the same, one end of said pipe having an air-tight closure, a liquid rising in the other end of said pipe, and means for drawing a cable through said pipe and said liquid.

In testimony whereof I affix my signature 75 in presence of two witnesses.

EMIL PASSBURG.
